UNITED STATES PATENT OFFICE

159,769

SPOON

Corinne A. Zinn, Fort Worth, Tex.

Application August 15, 1947, Serial No. 140,906

Term of patent 14 years

(Cl. D44—29)

To all whom it may concern:

Be it known that I, Corinne A. Zinn, a citizen of the United States of America, residing at Fort Worth, in the county of Tarrant and State of Texas, have invented a new, original, and ornamental Design for a Spoon, of which the following is a specification, reference being had to the accompanying drawing, forming part thereof.

I claim:

The ornamental design for a spoon, substantially as shown.

CORINNE A. ZINN.
